UNITED STATES PATENT OFFICE.

JENS LOHNE, OF FARNSUND, NORWAY.

MAGAZINE FOR SMALL-ARMS.

1,285,263.

Specification of Letters Patent. Patented Nov. 19, 1918.

Application filed August 2, 1918. Serial No. 248,052.

To all whom it may concern:

Be it known that I, JENS LOHNE, photographer, citizen of Norway, residing at Farsund, Norway, have invented certain new and useful Improvements in Magazines for Small-Arms, of which the following is a specification.

The present invention relates to improvements in magazines for rifles and has for its object a magazine which is capable of carrying a greater number of cartridges than gun magazines formerly known. The present construction is especially adapted for automatic small-arms.

15 The capacity for holding a great number of cartridges is obtained by giving the magazine a screw-shaped form, and the cartridges lie alongside the body of the screw and between the threads thereof.

20 An embodiment of the invention is shown in the accompanying drawing, in which:

Figures 1 and 2 show a side and top view respectively of a gun equipped with the side magazine.

25 Fig. 3 shows the magazine itself with the inner screw-shaped part drawn out partly.

Figs. 4 and 5 show a top and end view respectively of details of the cartridge-feeding device.

30 Figs. 6 and 7 show, schematically, two forms of construction employed in feeding the cartridges forward and for introducing the cartridges into the barrel of the gun.

In the construction shown, the magazine 35 is connected to an automatic gun of a known type, in which the powder gases generated during firing are used to operate a piston which is connected to the breech-block for opening the same, closing of the breech-block being carried out by means of spring pressure.

The magazine, which is placed under the lock case and alongside of the butt end 40 of the gun, comprises an outer hol-

45 low cylinder 15 of sheet steel into whose walls on the interior is pressed a spiral groove 16. In this groove a screw-thread 17 corresponding to the groove 16 is placed. The core of this screw is in the form of a hollow cylinder 18.

Between these two cylinders 15 and 18 a spiral passageway is formed by the thread 17, which corresponds with the diameter and the length of the cartridges. When the magazine is filled, the cartridges 55 are arranged with their sides toward the inner cylinder 18 and they contact at the front and rear with the thread 17. By forming the magazine in this manner a greater number of cartridges can be stored 60 than in any magazine formerly known.

The cartridges are driven toward the gun barrel by means of the following arrangement:

The wall of the inner cylinder 18 is 65 provided throughout its entire length with a spiral slot 19, which is located intermediate the screw-threads 17 and has the same pitch as the screw threads. In this slot a slide 20 travels, whose foot 21 70 (see Fig. 6) slides in guides 22, 23, made of steel. The guides are situated in the inner cylinder 18 and consist of two arms 22 and 23, the first of which 22 is slotted throughout its entire length by a slot 24 in which the tongue 25 (see Fig. 3) of the slide 20 travels. Throughout the entire length of the other arm 23 a groove extends for 75 guiding the foot 26 of the slide (see Fig. 6).

The arms 22, 23 are of the same length as the magazine and carry at their front end a cover 27 for the front end of the magazine. The front face of the cover is 85 provided with a gear 28 with which a smaller gear 29 meshes. This gear 29 is mounted on a fixed shaft 30 which extends into a spring case 31 located on the side of the gun (see Figs. 1 90 and 2). This case contains a strong spiral spring (not shown) which may be wound up by means of an outer crank-handle 32.

After the spring (hereinafter called the 95 magazine spring) has been wound up by turning the crank 32 (and the gear 29) in direction of the arrows in Figs. 1 and 3, the arms 22 and 23 will be rotated in the direction of the hands of a watch 100

(as seen from the front end of the magazine), and this causes the slide —20— to travel rearwardly along the slot —19— until it reaches the rear end of the magazine. 5 At this position of the slide the magazine is filled. When the crank handle —32— is released the spring will unwind and cause the slide —20— to be driven forward, and this causes the cartridges to be moved forward toward the gun barrel. Some stopping device for the gear which may be managed from the outside of the gun may be employed if desired. Such a device is shown in Fig. 5 in which a pawl —32— is 10 used to stop the gear —29—. When the magazine is "opened," that is during the firing, the cartridge series are fixed by the leading cartridge which strikes against the closed breech block or against a knot in the 15 lock case upon which the breech block is acting.

In Fig. 6, I have shown one form of the device for feeding the cartridges forward to the lock case. As the cartridges reach 20 the lock case, they travel upward on an inclined guide —34— and are thereby lifted through an opening —35— (see Fig. 3) into the lock case, where they are caught by the breech block and led into the cartridge 25 chamber in the usual manner.

In the construction shown in Fig. 7, the slide —20— is formed as a head lying loose in the cartridge chamber. In this head a spring pressed flap —36— is arranged, 30 which extends to some degree into the slot —19— of the inner magazine sleeve —18— and against which the arm —22— of the interior guides act during the forward movement of the cartridges. In this construction, the high friction between the slide —20— and the guides —22, 23— is avoided and more force upon the cartridges is obtained. When the spiral spring in the 35 casing —31— is wound up, the spring 40 pressed flap —36— during the tightening of the spiral spring at each turn will travel over the arms —22, 23—. The slide head —20— in this incident is moved rearwardly with the cartridges during the filling of the 45 magazine and acts as a guide for the cartridges, preventing the same from sticking fast or turning across the magazine. A 50 slide of this construction is preferred to the form shown in Figs. 3, 4 and 6. After 55 the magazine has been filled, the spiral spring is wound up by means of the crank handle —32—.

The reloading of the magazine may be 60 accomplished in different ways. It may be accomplished by introducing the cartridges through the magazine opening —87— (see Figs. 1 and 2) after the slide —20— has been led back to its rear position. The magazine can be made removable if desired

and may be replaced by another filled magazine. 65

The magazine can be adapted to different types of guns and adjusted for a greater or lesser number of cartridges by altering the diameter and length of the cylinders. 70

If the spiral spring in the case —31— should not be capable of bringing forward the cartridges in a large magazine, an auxiliary spring may be placed in the rear of the magazine to assist in the operation. 75

In the above specification the magazine is described as of a cylindrical form, but the form may of course be changed without departing from the spirit of the invention. 80

I claim:

1. A magazine for fire-arms comprising a casing having a core located therein and spaced away from the wall thereof, a spiral thread located in the space and forming a spiral passageway for the cartridges, and a member movable in a spiral path along said passageway for moving the cartridges forward. 85

2. A magazine for fire-arms comprising a casing having an interior spiral groove, a core located in the cylinder and spaced away from the wall thereof, a spiral thread carried by the core and engaging the spiral groove, said thread forming a spiral passageway for the cartridges between the core 90 and casing, and a member movable in a spiral path along said passageway for moving the cartridges forward. 95

3. A magazine for fire-arms comprising a casing having a hollow core located therein 100 and spaced away from the wall thereof, a spiral thread located in the space and forming a spiral passageway for the cartridges, said core having a spiral slot placing its interior in communication with the passageway, and a member extending through said slot and projecting into the passageway for moving the cartridges forward. 105

4. In a construction as called for by claim 3, means extending through the core and 110 engaging the member for operating the same.

5. In a construction as defined in claim 3, a rotatable guide located in the interior of the core and engaging the member for moving the same along the spiral slot when the 115 guide is turned.

6. A magazine for fire-arms comprising a casing, a hollow core located in the casing and spaced away from the wall thereof, a spiral thread located in the space and forming a spiral passageway for the cartridges, said core having a spiral slot placing the interior of the core in communication with the passageway, a slide movable along said 120 passageway, a rotatable member mounted in the core, and means connecting the rotatable member and slide. 125

7. A magazine for fire-arms comprising a casing, a hollow core located in the casing and spaced away from the wall thereof, a spiral thread located in the space and forming a spiral passageway for the cartridges, said core having a spiral slot placing the interior of the core in communication with the passageway, a slide movable along said passageway and having a spring pressed 10 flap extending through the slot into the in-

terior of the core, and a rotatable member located on the interior of the core and engaging the flap for moving the slide along the spiral passageway.

In testimony whereof I affix my signature 10 in presence of two witnesses.

JENS LOHNE.
